UNITED STATES PATENT OFFICE.

FRANK REESE, OF MINNEAPOLIS, MINNESOTA.

SCREEN FOR SWINGING SASH.

1,343,933.

Specification of Letters Patent. Patented June 22, 1920.

Application filed August 11, 1919. Serial No. 316,603.

To all whom it may concern:

Be it known that I, FRANK REESE, citizen of the United States, residing at Minneapolis, in the county of Hennepin and State of Minnesota, have invented certain new and useful Improvements in Screens for Swinging Sash; and I do hereby declare the following to be a full, clear, and exact description of the invention, such as will enable others skilled in the art to which it appertains to make and use the same.

My invention has for its object to provide an improved device or means for mounting the screen of a window sash.

Particularly, the invention relates to a metallic sash mounted for pivotal movements in a steel frame work, for the purpose of ventilating a building.

The invention is illustrated in the accompanying drawings, wherein like characters indicate like parts throughout the several views. Referring to the drawings:

Figure 1 is a fragmentary view in elevation looking at the sash and frame structure from the exterior of the building, some parts being broken away and some parts being removed;

Fig. 2 is a view looking at the sash and frame work from the inner side of the building, some parts being broken away and some parts being removed;

Fig. 3 is a vertical section taken on the line 3—3 of Figs. 1 and 2, some parts being broken away; and Fig. 4 is a view corresponding to Fig. 3, with the exception that the window sash is open.

The frame work in which the window sash is mounted, is formed by vertical members 4 and horizontal members 5. The frame 6 of the window sash at its vertical central portion is provided with a cross bar 7 shown as in the form of an angle iron, same being secured to the inner side of the window sash 6, and inwardly offset from the glass panes 8 of the said window sash. The said window sash 6, as shown, has a horizontal muntin 9 that separates the upper and lower panes. The cross bar 7 is provided with a rigidly secured thin sheet metal blade 10, that projects into close contact with the upper pane.

The window sash 6 in line with the ends of the cross bar 7, is pivotally connected to the vertical members 4 of the frame work at 11, and the said window sash is thus mounted so that when swung on said pivots from a

closed to an open position, its lower portion will move outward and its upper portion will move inward. The flange weathering bar 12 is rigidly secured to the upper muntin 5 and its outer flange overlaps the upper portion of the window sash 6. The upper portion of said window sash 6 is provided with an outwardly extended joint flange 13 that overlaps the inner edge of the weathering bar 12. At its lower portion said window sash 6 is provided with a depending joint flange 14 that overlaps the outer portion of the lower muntin 5. The numeral 15 indicates the two-part metal screen frame 70 which, as shown, is detachably but rigidly secured in a position by means of turn-buttons 16 applied to the interior weathering bars and by headed studs 17 applied to a supplemental bar 18 which, as shown, is secured to the lower muntin 5. The upper flange section of the screen frame 15 is provided with a joint-plate 19, the upper edge of which, is shown as bent over to form a rounded surface that has contact with the angle iron cross bar 7, approximately in line with the projected axes of the pivots 11, but so far as this invention is concerned, this frame 15 may be of any suitable construction. When the window sash is moved on pivots 11 from its closed into an open position, the bar 7 being at the axis of the pivot, serves as a pivot bar to maintain contact with the joint plate 19 of the lower screen 15, and the screen wire cloth 15^a will 80 cover the space opened by the lower portion of the window sash. The space opened by the upper portion of the window sash is kept covered by screen wire cloth 20^a held in a rectangular frame 20 which is preferably of substantially the same type as the screen frame 15. The said screen frame 20, as shown, and preferably, is made up of two angle iron frame sections having their inner flanges telescoped and rigidly connected together and to the screen 20^a. Said frame is therefore formed with an annular channel that is open at sides, bottom and top. The sides of the frame 20 work loosely but in quite close engagement with the inner surfaces of 90 a pair of laterally spaced upright side plates 21, which by brackets 22 are secured to the upright frame members 4. The inner face of the upper portion of the screen frame 20 rests against the depending outer flange of 100 the weathering bar 12. Studs or guide pins 23 that project inward from the upper por-

tions of the side plates 21, work in channeled sides of the screen frame 20 and guide the upper portion thereof, vertically, while permitting the same to slide and to swing at its lower portion. The lower edge of the screen frame 20 rests on a lower joint plate 24 that is secured to the muntin 9 of the window sash 6 and projects outward therefrom and terminates preferably in a turn-bead 25. This bead 25 is positioned in the channel of the lower portion of the screen frame 20 and is loosely connected to the inner flange of said frame by a small screw or pin 26 that permits a slightly turning movement of the bead within the channel of said frame 20.

When the window sash 6 is moved pivotally from its closed to its open position, the beaded edge 25 of the joint plate 24, and consequently the lower edge of the screen frame 20, will be given an outward and slightly upward movement on the arc of a circle, center of which is at the axis of pivot 7; and under such movement the screen frame 20 will be raised bodily and given an outward oscillatory movement on the guide pins 23 which latter act as pivots and permit sliding movements of the said screen frame 20. Under all such movements of the screen frame 20, the side plates 21 keep closed the space between the vertical side and edges of said frame 20 and the corresponding sides of the frame work. The screen frame 20 is gravity seated and held on the joint plate 24, but its seating thereon under all conditions, is insured by the screw or pin 26. It is therefore obvious that the adjustable outer screen will automatically adapt itself to all positions of the window sash and is also evident that this adjustable screen may be very quickly and easily applied, and while highly efficient for the purposes had in view, is of simple construction and of relatively low cost.

What I claim is:

1. The combination with a frame work and a window mounted therein on intermediately located pivots, of a screen seated at its lower edge on a bar carried by said sash at a point offset from its pivot, the said screen at its upper portion being seated against the upper portion of said frame work for pivotally sliding movements.

2. The combination with a frame work and a window sash mounted therein on intermediately located pivots, of a screen seated at its lower edge on a bar carried by said sash at a point offset from its pivot, the said screen at its upper portion being seated against the upper portion of said frame work for pivotally sliding movements, and

means closing the spaces between the sides of said screen and sides of said frame work.

3. The combination with a frame work and a window sash mounted therein on intermediately located pivots, of a screen seated at its lower edge on a bar carried by said sash at a point offset from its pivot, the said screen at its upper portion being seated against the upper portion of said frame work for pivotally sliding movements, means closing the spaces between the sides of said screen and sides of said frame work, and a lower screen relatively fixed to said frame work and contacting with a portion of said window sash approximately at the axis of its pivot.

4. The combination with a frame work and a window sash pivotally connected thereto at its intermediate portion by pivots located inward of said sash, said sash having a cross bar approximately at the axis of its pivot, of a relatively fixed lower screen applied to the inner side of said frame work and having a joint flange contacting with the axial cross bar of said sash, said sash having a lower joint plate projected outward therefrom, an outer screen having a frame seated on said lower joint plate, means guiding the upper portion of the frame of said outer screen for sliding in pivotal movements in close engagement with the upper portion of said frame, and side plates secured to the sides of said frame work and embracing the sides of the frame of said outer screen in all positions thereof.

5. The combination with a frame work and a relatively fixed lower screen, of a swinging window sash, of an inside pivot structure having means securing the same to intermediate portion of said window sash including a recessed cross bar and a filler strip extending from said bar to the glass of the window sash, said screen having a projecting flange engaging the recess of said cross bar approximately at the axis of oscillation of said pivot structure.

6. The combination with a frame work and a window sash mounted therein on intermediately located pivots, of a screen which at its lower edge is hingedly connected to the intermediate portion of said sash at points offset from the sash pivot and at its upper edge is connected to the upper portion of said frame for a combined pivotal and sliding movement.

In testimony whereof I affix my signature in presence of two witnesses.

FRANK REESE.
